Attorney

UNITED STATES PATENT OFFICE.

CHARLES ARTHUR BREEN, OF MOOSE LAKE, MINNESOTA.

LANTERN.

Application filed April 2, 1925. Serial No. 20,302.

To all whom it may concern:

Be it known that I, CHARLES A. BREEN, a citizen of the United States, residing at Moose Lake, in the county of Carlton and State of Minnesota, have invented certain new and useful Improvements in Lanterns, of which the following is a specification, reference being had to the accompanying drawings.

This application is for the subject matter of my prior abandoned application, Serial No. 33,175, filed June 9, 1915, for lanterns, and the invention relates to new and useful improvements in lanterns and as its principal object aims to provide a novel form of adjusting mechanism for the chimney, whereby the same may be easily and quickly swung from position over the lamp wick to an out-of-the-way position to permit the cleaning or trimming of the wick.

Another and more specific object of the invention is to provide a lantern chimney adjusting mechanism which is so designed that it may be operated to first lift the cap from over the chimney, to immediately and subsequently lift the chimney and dispose its lower terminal above the burner of the lamp, and to then swing the chimney out of the lantern frame.

The above and other incidental objects of a similar nature, which will be hereinafter more specifically treated, are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced to practice, and throughout the several views of which similar reference numerals designate corresponding parts,

Figure 1 is a front elevation of a lantern embodying the features of my invention, and indicating in dotted lines the position which the lamp chimney assumes when operated upon by the adjusting mechanism to swing it out of the lantern frame;

Figure 2 is a section on the line 2—2 of Figure 1;

Figure 3 is a detail view in longitudinal section, illustrating the manner in which the

chimney and cap supporting wires or rods 55 are engaged with the slidable sleeve;

Figure 4 is a view in perspective, detached, of the upper loop and its concomitant parts as herein embodied.

In taking up the detailed description of the invention, as embodied in the accompanying drawings, reference will first be had particularly to Figure 1, wherein the lantern is illustrated as an operative entirety. In this figure, the lantern which is of conventional design, is shown as including a base 10; a substantially rectangular frame 11, which rises from the base; a vertically adjustable cap 12, which is adapted to normally engage over the ends of the chimney 13, for holding this member in the proper position over the burner 14, and a bail 15, by means of which the lantern may be transported.

The elements of construction above enumerated are all of conventional and standard design and since they do not form any part of the present invention, need not be further described in detail.

Upon one of the vertical members of the frame 11, is slidably mounted a sleeve 16, which member is preferably formed from a metallic tube of brass or other sheet metal.

Extending laterally from the upper terminal of the sleeve is a hoop 17, and from a point adjacent the lower terminal of the sleeve, extends a hoop 18. Each of these hoop members is formed preferably from a single length of wire of relatively heavy gage. The two terminal portions of the upper hoop are extended laterally from the chimney, as indicated at 19, and are then bent downwardly at right angles, as at 20. At the lower terminals of the depending portions 20, are formed the coils 21 and from these coils the horizontal portions 22 extend to the sleeve. The horizontal portions 22 are coiled about the sleeve 16, as indicated at 22' and are freely engaged with the sleeve so that the sleeve may slide within the coils for a purpose which will hereinafter become apparent.

As will be readily observed upon reference to Figure 1, the upper hoop is adapted to embrace the upper terminal of the chimney. The two portions of the lower hoop are extended outwardly in a horizontal plane, as at 23, and are then directed upwardly and

at right angles, as at 24. The upper terminals of these portions 24 are directed outwardly at 25 and coiled about the sleeve.

One convolution of the coil is, as shown 5 best in Figure 1, provided with a vertically extending loop *a*, which surrounds a stud or pin *b* carried by the sleeve 16. The coiled portions of the members 25 are freely slideable on the sleeve and are held against rotation thereon by means of the stud *b*, which as shown in Figure 1, engages with the arms of the loop *a* to prevent the turning of the coils upon this sleeve.

It is now to be explained that the hoop 15 member 18 may be expanded against the tension of the wire from which it is formed, to permit a new lamp chimney to be introduced, whenever occasion may demand. It is also to be explained that the hoops are 20 adapted to grip the chimney with sufficient force to support this member when the chimney is moved out of the lantern frame in the manner disclosed in Figure 1.

A horizontal stop pin or equivalent device, indicated at 26', is carried by the vertical arm of the frame 11, upon which the sleeve is mounted so that this member will be limited in its downward sliding movement. A handle, indicated at 26, is applied 30 to the sleeve 16.

When the sleeve is manipulated in a manner to be hereinafter explained, to swing the chimney out of the lantern frame, it is of course, requisite that the vertically adjustable cap 12 be elevated and disengaged from the upper terminal of the chimney before this member can be swung outwardly. For this reason, the cap 12 is connected to the upper end of the sleeve 16 by means of the 40 arm 27 formed of wire or a small rod. The outer end of this arm 27 is passed around the lower end of the cap, forming an embracing hoop and is directed outwardly in a horizontal plane for a short distance as in Figure 1. The wire is then directed downwardly, as at 28 and thence outwardly, as at 29, and finally coiled about the upper end of the sleeve, as illustrated in detail in Figure 3. An annular groove or recess, indicated 45 at 30, is formed in the sleeve so that the attached terminal of the arm 27 will freely receive the sleeve to permit of rotation of the sleeve with respect to the arm, but will be held against vertical movement on the sleeve.

55 The actual construction and arrangement of the several parts of the invention, being thus disclosed, it now remains to describe the manner in which the chimney adjusting mechanism may be manipulated to swing the chimney out of the frame. In this connection, reference will now be had particularly to Figure 1. As therein shown, the operator may, by lifting up on the handle 60 26, cause the cap 12 to be first lifted and 65 disengaged from the upper end of the chim-

ney by means of the arm 27. As shown in Figure 1, the initial opening movement of the sleeve, during the lifting of the cap 12, will not affect the position of the chimney 70 13 for the hoop or wire 18, which controls the lifting of the chimney is not acted upon by the sleeve, until the cap 12 has been lifted a sufficient distance to disengage it from the upper terminal of the chimney. Obviously, the continued upward movement 75 of the sleeve 16, after the stud *b* has been engaged with the top of the loop *a* will cause the chimney to be lifted so as to dispose its bottom edge above the burner of the lamp. During the lifting of the chimney, the cap, of course, continues its upward movement and, therefore, remains disengaged from the upper end of the chimney. After these two steps of lifting the cap 12 and subsequently lifting the chimney 13 to 80 position above the burner have been completed, the handle 26 may be turned to rotate the sleeve 16 with a consequent removal of the chimney from the lantern frame. The chimney may, in this manner, be swung to 85 an out-of-the-way position, to the side of the frame, as indicated in dotted lines in Figure 1.

While I have found the bending of the 90 hoop forming wires in the manner above explained, to be productive of the greatest efficiency in the construction of the lamp, I desire to explain that under some circumstances, particularly when the lamp is of a different construction from that shown in 95 the accompanying drawings, various minor changes may be made in the specific shape 100 of the hoop wires.

If desirable, a hoop indicated at 31, may be provided to surround the chimney immediately above the base thereof, as in Figure 1. This hoop is secured at one side to the member 24 and is accompanied at a diametrically opposite point, by a vertical post 32, which is connected to the member 18, as in Figure 1.

In reduction to practice, it has been found that the form of this invention illustrated in the drawings, and referred to in the above description as the preferred embodiment, it is the most efficient and practical; yet realizing that the conditions concurrent with the adoption of this device will necessarily vary, it is desirable to emphasize the 110 fact that various minor changes in the details of construction, proportion and arrangement of parts may be resorted to, when required, without sacrificing any of the advantages of this invention, as defined by the 115 appended claim.

What is claimed, is:—

A lantern including a frame, a sleeve mounted to slide thereon upon a portion of the frame, a vertically movable chimney engaging cap, an arm engaging the cap and 120 125 130

embracing the sleeve, a member carried by the sleeve adapted to engage the base of a lamp chimney, and a loop adapted to embrace the upper terminal of the lamp chimney, said loop comprising a strand of material having its terminal portions extended laterally a predetermined distance and then bent downwardly at substantially right angles, the lower terminals of the depending portions being formed into coils and then extended at right angles to the depending portions and formed into loops, said loops embracing and freely engaging the sleeve. ¹⁰

In testimony whereof I hereunto affix my signature.

CHARLES ARTHUR BREEN.
